GAS LASER

Robert C. Rempel, Los Altos, Leslie L. Morris, Milpitas,
and Charles E. Jones, Sunnyvale, Calif., assignors to
Spectra-Physics, Inc., Mountain View, Calif., a corpora-
tion of California

Filed June 4, 1963, Ser. No. 75,212

Term of patent 14 years

(Cl. D26—14)

Des. 199,441

PAGE 2

FIGURE 1 is a top perspective view of a gas laser embodying our design;

FIGURE 2 is a side elevational view of the laser of FIGURE 1, the two sides being substantially identical in appearance;

FIGURE 3 is a left end view of the laser of FIGURE 1;

FIGURE 4 is a right end view of the laser of FIGURE 1; and

FIGURE 5 is a bottom perspective view of the laser of FIGURE 1.

We claim:
The ornamental design for a gas laser, as shown.
